UNITED STATES PATENT OFFICE.

HAROLD C. MATTHEWS, OF NEWARK, NEW JERSEY.
PICTURE-EXHIBITING DEVICE FOR TALKING-MACHINES.

996,101.

Specification of Letters Patent. Patented June 27, 1911.

Application filed August 20, 1908. Serial No. 449,392.

To all whom it may concern:

Be it known that I, HAROLD C. MATTHEWS, a citizen of the United States, residing at Newark, in the county of Essex and State of New Jersey, have invented certain new and useful Improvements in Picture-Exhibiting Devices for Talking-Machines, of which the following is a specification.

The objects of this invention are to provide means by which a magic lantern can be employed for exhibiting pictures in connection with the reproduction of a song or story by a talking machine; to enable the magic lantern to be automatically operated by the talking machine; to thus perfectly synchronize the reproductions by picture and by sound; to secure such synchronism automatically and without any attention whatever on the part of the operator; to obtain a practically instantaneous admission and cut-off of light, in the magic lantern; to enable a quick and easy change to be made from one series of pictures to another; to secure a simple, effective and practical construction, and to obtain other advantages and results as may be brought out in the following description.

Referring to the accompanying drawings, in which like numerals of reference indicate the same parts in the several figures, Figure 1 represents a front view of a magic lantern connected to a cylinder talking machine by my improved means, and Fig. 2 is a side view of the magic lantern and my attachments; Fig. 3 is a face view of a certain picture disk; Fig. 4 is a rear view of the said magic lantern with the lamp house removed; Fig. 5 is a horizontal section of a portion of the operating mechanism taken on line 5, 6, Fig. 4, looking downward; Fig. 6 is a section taken on the same line 5, 6, Fig. 4, looking in the opposite direction or upward; Fig. 7 is a side view of a certain connecting bar and rack; Fig. 8 is a perspective view of a certain split collar and means for securing the same to the reproducer arm of a talking machine; Fig. 9 is a horizontal section taken longitudinally of the picture disk shaft; Fig. 10 is a rear view of a certain shutter and its detent in closed position, the operating arm and other parts being removed for greater clearness; Fig. 11 is a rear view of the shutter operating arm detached, and Fig. 12 is an edge view of the same.

In said drawings, 10 indicates a talking

machine of the cylinder type, and 11 a magic lantern to which my improvements are shown applied.

The magic lantern comprises a suitable base 12 upon the rear of which is mounted a lamp-house 13 of any suitable and well-known construction, having a tube 14 through which the light is concentrated upon the picture, as usual. The picture or series of pictures 15 are arranged in a circular row of apertures 16 in a disk 17, which is upon a shaft 18 journaled horizontally and parallel to the pencil of light from the lamp, in a vertical plate 19 at the front end of the base 12. The said plate 19 has an opening 20 into registration with which the pictures 15 are successively brought by rotation of their carrying disk 17, said disk being at the front side of the plate 19, or side away from the lamp. This picture disk 17 is of course removable, so as to enable different pictures to be displayed at different times, and I have shown for holding it upon the shaft 18, a nut 21 on the threaded end of said shaft 18 adapted to clamp the picture disk against a flange 22 fixed upon a shoulder of the shaft. This flange 22 is adapted by its position at the front of the plate 19, to prevent rearward longitudinal movement of the shaft 18 in its bearings. Preferably the picture disk has a radial extension 171 of its central hole 170 to receive the shaft 18, which extension receives a corresponding radial projection 172 on the shaft, to insure said picture disk 17 being put on the shaft in correct position, as will be understood.

As the disk 17 is rotated, its different pictures are brought successively in front of the opening 20 of the plate 19, and thus displayed. I will next describe the means for automatically turning said disk by the operation of the talking machine.

At the rear side of the plate 19 a bearing 23 for the shaft 18 projects, as shown in Figs. 5 and 9, said bearing being held by screws 24 or the like to the supplemental plate 25 which covers a portion of the upright plate 19 as hereinafter more fully described. At the rear end of the bearing 23 a star wheel 26 is fixed on the shaft 18, which star wheel is adapted to be engaged and turned by pins 27 on the side of a wheel 28 rotatably mounted upon the rear of the upright plate 19. This wheel has at its opposite side another series of pins or teeth 29 which are engaged by a rack 30 adapted to

slide transversely of the upright plate 19. Longitudinal movement of this rack thus turns the picture disk.

Preferably, the rack 30 is slotted longitudinally, as shown at 31, to receive studs 32, 33 on the plate 19 and be supported thereby as it slides. To the end of said rack next the talking machine 10, is pivoted one end of a bar 33, the other end being notched at 34 in Fig. 1, and adapted to hook over a pin 35 on a sleeve 36 which can be clamped upon the reproducer arm 37 of the talking machine by means of screws 38, all as shown more particularly in Fig. 8. The bar 33 thus lies longitudinally of the talking machine cylinder, or parallel thereto, so that as the reproducer moves along its rod 39, it draws the bar 33 and slides the rack 30. The hinging of the bar 33 to the rack 30 accommodates any differences in height between the magic lantern and talking machine, and furthermore enables the bar to be folded in over the magic lantern when not in use. The end of the bar 33 is provided with a plurality of notches 34, which provide for adjustment in making the connection of said bar to the reproducer of the talking machine.

During intervals in which the pictures are being changed by rotating the picture disk 17, an automatic shutter 40 closes the opening 20, and shuts off the rays of light coming from the lamp-house, so as to obviate all blur of a combination of two pictures while moving. This shutter 40 is hung by a stem 41 directly above the opening 20, so that it naturally falls into closed position, as shown in Fig. 10. An arm 42 pivoted at its lower end 43 to the rear side of the plate 19 just below the shaft 18 and at the side thereof away from the wheel 28, is weighted as at 44 to normally fall at its upper end against the stem 41 of the shutter 40 and open said shutter, as shown in full lines in Fig. 4. Said upper end of the arm 42 preferably has a forwardly projecting pin 45 to engage the stem as described, and furthermore a handle 46 may project from this end of the arm 42 to enable it to be drawn or tipped into idle position. This handle 46 and pin 45 are preferably formed of a single piece of wire bent as shown in Fig. 6 more especially. For automatically releasing the said arm 42 for the change of pictures, said arm is provided at its side next said wheel 26 with a projection or tooth 47 which is adapted to be engaged at the proper moments by the pins 27 of the wheel 28 which turn the picture disk shaft 18, as above described. This tooth 47 is so located that each pin 27 engages it just before engaging a point of the star wheel 26, and thus pushes back the said arm, releasing the shutter 40 for the whole time the disk is being turned. The pin 27 then passes the tooth 47 as it does the point of the star wheel 26,

and the arm 42 falls back against the shutter stem, with sufficient force to open said shutter, and open it suddenly.

The pushing back of the arm 42 by the tooth 47 is gradual, and to prevent the closing of the shutter being likewise gradual, I have provided a detent 48 for the stem 41 of the shutter. This detent is pivoted on the supplemental plate 25, and adapted at its outer end 49 to receive the extremity 50 of the stem when the shutter is in open position, and by its weight hold the shutter raised or open. When the pin 45 of the arm 42 begins to move, therefore, in its retraction, the shutter does not at once follow it, but the pin moves idly to a point where the shutter can freely drop entirely closed, and then said pin engages a projection 51 of the shutter stem, releasing it from the detent and letting the shutter drop by gravity. A practically instantaneous closure of the opening 20 is thus secured, as well as the substantially instantaneous opening above described. A pin 57 holds the detent 48 from dropping down too far when idle.

In the operation of the devices described, let it be supposed that the talking machine is running and the magic lantern parts are as shown in Fig. 4, so that a picture is being thrown on the screen through the hole 20. The talking machine continues to run, its reproducer pulling through the rod 33 upon the rack 30 which in turn rotates the wheel 28, until the next pin 27 of said wheel engages the projection 47 of the arm 42 and slowly pushes said arm backward, or toward the right hand side of said Fig. 4. As the arm 42 swings, it leaves the shutter 40 as shown in Fig. 4 until the pin 45 of the arm engages the projection 51 of the shutter stem 41; this forces the shutter free from its detent 48, and it drops instantly to close the opening 20, the pin 45 having passed out of the way. The pin 27 of the wheel 28, by its continued movement, carries the arm 42 still farther back and at the same time engages the star wheel 26 to turn the same a tooth; this brings the next picture in front of the opening 20, and upon the release of said tooth and also projection 47 of the arm, said arm falls forward, its pin 45 engaging the stem 41 of the shutter 40 and forcing the same into open upper position as shown in Fig. 4. The detent 48 catches the extremity 50 of the shutter stem, and thus the parts are again in the relation shown in Fig. 4, with the next picture being exhibited.

It will be noted that the plate 19 is recessed at its back, as at 52, to receive the parts above described for operating the picture disk and shutter, and preferably all said parts are mounted for convenience upon the supplemental plate 25 above referred to and which is removably secured to the main plate 19 by screws 53. Even this supple-

mental plate is shown recessed as at 56 to receive the finger 45 of the arm 42 in its swinging movement. Furthermore, I desire to point out that by changes in the positions 5 of the pins on the wheel 28, the time of displaying the pictures of a series could be varied. I have therefore shown in the wheel 28 a series of outer holes 54, in any of which the pins 27 may be arranged, and likewise an 10 inner series of sockets 55 for the pins 29, it being understood that the said pins 27 and 29 are removable. The same result of variation in time of picture display could obviously be obtained by changing the entire 15 wheel 28, or by using differently toothed racks to actuate the wheel.

Having thus described the invention, what I claim as new is:

1. The combination with a talking machine having a traveling reproducer and means for driving the same and a magic lantern having a picture disk shaft, of a rotary member connected to said shaft and means for mechanically transmitting linear movement of said reproducer into rotation of said rotary member.

2. The combination with a talking machine having a traveling reproducer and means for driving the same and a magic lantern having a picture disk shaft, of a shutter adapted to cut off the light of the magic lantern from said picture disk, and means for mechanically transmitting motion to said shaft and shutter from the said reproducer of the talking machine.

3. The combination with a talking machine having a traveling reproducer and means for driving the same and a magic lantern having a picture disk shaft and a shutter, of a rotary member connected to said shaft and shutter, and means for mechanically transmitting linear movement of said reproducer into rotation of said rotary member.

4. The combination with a talking machine having a traveling reproducer, and a magic lantern having an apertured plate, of a picture disk shaft rotatably mounted in said plate, a rack slidably mounted on said plate, means for transmitting motion from said rack to said shaft intermittently, and a connecting rod pivoted at one end to said rack and adapted at its other end to be attached to the reproducer arm of the talking machine.

5. The combination with a talking machine having a traveling reproducer, and a magic lantern having an apertured plate, of a picture disk shaft rotatably mounted in said plate, a star wheel on said shaft, a rack slidably mounted on said plate, a wheel pivoted on said plate and engaged by said rack, pins on said wheel adapted to engage said star wheel, and a connecting rod pivoted at one end to said rack and adapted at its other

end to be attached to the reproducer arm of the talking machine.

6. The combination with a talking machine having a traveling reproducer, and a magic lantern having an apertured plate, of a picture disk shaft rotatably mounted in said plate, a star wheel on said shaft, a rack slidably mounted on said plate, a wheel pivoted on said plate and engaged by said rack, adjustable pins on said wheel adapted to engage said star wheel, and a connecting rod pivoted at one end to said rack and adapted at its other end to be attached to the reproducer arm of the talking machine.

7. The combination with a talking machine having a traveling reproducer, and a magic lantern having an apertured plate, of a picture disk shaft rotatably mounted in said plate, studs on said plate, a rack slotted to receive said studs and slidable thereon, a wheel pivoted on said plate and engaged by said rack, pins on said wheel adapted to engage said star wheel, and a connecting rod pivoted at one end to said rack and adapted at its other end to be attached to the reproducer arm of the talking machine.

8. The combination with a talking machine having a moving reproducer, of a magic lantern having an apertured plate, means for displaying pictures through said aperture, a shutter for said aperture, a pivoted arm adapted to operate said shutter, a rack slidably mounted on said plate, means for transmitting motion from said rack to said arm intermittently, and connections between said rack and the reproducer of the talking machine.

9. The combination with a talking machine having a moving reproducer, of a magic lantern having an apertured plate, means for displaying pictures through said aperture, a shutter normally closing said aperture, a pivoted arm adapted to open said shutter, a rack slidably mounted on said plate, means for transmitting motion from said rack to said arm intermittently, and connections between said rack and the reproducer of the talking machine.

10. The combination with a talking machine having a moving reproducer, of a magic lantern having an apertured plate, means for displaying pictures through said aperture, a shutter normally closing said aperture by gravity, a pivoted arm adapted to open said shutter, a rack slidably mounted on said plate, means for transmitting motion from said rack to said arm intermittently, and connections between said rack and the reproducer of the talking machine.

11. The combination with a talking machine having a moving reproducer, of a magic lantern having an apertured plate, means for displaying pictures through said aperture, a shutter for said aperture normally closing by gravity, a detent adapted

4
to hold said shutter open, a pivoted arm adapted to operate said shutter, a rack slidably mounted on said plate, means for transmitting motion from said rack to said arm intermittently, and connections between said rack and the reproducer of the talking machine.

12. The combination with a talking machine having a moving reproducer, of a magic lantern having an apertured plate, means for displaying pictures through said aperture, a pivoted shutter for said aperture normally closing by gravity, a pivoted arm adapted to open said shutter, a rack slidably mounted on said plate, means for transmitting motion from said rack to said arm intermittently, and connections between said rack and the reproducer of the talking machine.

13. The combination with a talking machine having a moving reproducer, of a magic lantern having an apertured plate, means for displaying pictures through said aperture, a shutter pivoted by a stem and adapted to normally close said aperture by gravity, a pivoted arm adapted to engage said stem to operate the shutter, and means for transmitting motion from the reproducer of the talking machine to said arm to swing the same.

14. The combination with a talking machine having a moving reproducer, of a magic lantern having an apertured plate, means for displaying pictures through said aperture, a pivoted shutter adapted to normally close said aperture by gravity, a detent for holding said shutter open, a pivoted arm adapted to engage said shutter stem to open the shutter, means adapted to be engaged by said arm to release the said detent, and connections for transmitting motion from the reproducer of the talking machine to said arm to swing the same.

15. The combination with a talking machine having a moving reproducer, of a magic lantern having an apertured plate, means for displaying pictures through said aperture, a shutter for said aperture pivoted

by a stem, a projection on said stem at the opposite side of its pivotal point from the body of the shutter, a pivoted arm adapted to engage said stem to open the shutter and said projection to close it, and means for transmitting motion from the reproducer of the talking machine to said arm to swing the same.

16. The combination with a talking machine having a moving reproducer, of a magic lantern having an apertured plate, means for displaying pictures through said aperture, a shutter for said aperture pivoted by a stem, a projection on said stem at the opposite side of its pivotal point from the body of the shutter, a pivoted arm adapted to engage said arm to open the shutter and said projection to close it, a detent for the shutter, and means for transmitting motion from the reproducer of the talking machine to said arm to swing the same.

17. The combination with a plate having a display aperture, of a shutter adapted to normally close by gravity, an arm pivoted at one end and adapted at its other end to open said shutter by gravity, and means for intermittently retracting said arm from the shutter.

18. The combination with a plate having a display aperture, of a shutter adapted to normally close by gravity, an arm pivoted at one end and adapted at its other end to open said shutter by gravity, means for intermittently retracting said arm from the shutter, and a detent for said shutter.

19. The combination with a plate having a display aperture, of a shutter adapted to normally close by gravity, an arm pivoted at one end and adapted at its other end to open said shutter by gravity, means for intermittently retracting said arm from the shutter, and means adapted to be engaged by said arm to release said detent.
